ROLLER SKATES

Eugen Kardhordo, Bratislava, Czechoslovakia,
assignor of one-half to Sigma Pumps, National
Corporation, Olomouc, Czechoslovakia

Application December 10, 1947, Serial No. 790,847
In Czechoslovakia January 10, 1947

3 Claims. (Cl. 280—11.22)

1

My invention relates to roller skates and more particularly to roller skates suitable for roller skating in which at least three rollers or wheels are arranged in tandem formation.

The main object of this invention is to provide an improved roller skate of the said type which will allow quick starts and sudden stops without impairing a safe support for the user of the skate, and which will permit to attain high speed even in quick and sharp turns.

According to my invention my improved roller skate comprises at least two auxiliary rollers and an intermediary main roller arranged in a single track the convex running surface of all rollers contacting the supporting surface when the rollers rotate in a plane essentially perpendicular to the supporting surface, and the convex running surfaces of the auxiliary rollers being differently shaped to consecutively disengage from the supporting surface with increasing inclination of their plane of rotation.

My invention and its objects will be more fully understood from the following specification when read with the accompanying drawing in which

Fig. 1 is a plan view of my improved roller skate taken from underneath and showing a skate containing three rollers or wheels arranged in alignment,

Fig. 2 is an elevational view to Fig. 1 partly in section,

Fig. 3 illustrates diagrammatically cross section of the rollers in planes passing through their axis of rotation while the plane of rotation of said rollers is perpendicular to the racing surface;

Fig. 4, which corresponds to Fig. 3, shows a different inclination of the plane of rotation of the rollers in respect to the racing surface,

Fig. 5 is a section on the line 5—5 in Fig. 2,

Fig. 6 is a similar section of another embodiment,

Fig. 7 is a side view showing the rear part of a roller skate in the embodiment shown in Fig. 6, and

Figs. 8 and 9 show in cross section and in partial side view, respectively, still another embodiment of the rollers used in my improved skates.

As shown in Figs. 1, 2, 5, the frame 1 of the skate is provided with suitable foot plates 2, 3. Three rollers or wheels 4, 5, 6 are mounted preferably upon ball bearings in the frame 1 behind each other in the direction of racing. Said rollers are of different size and have differently shaped running surfaces clearly appearing from

2

Fig. 1 and schematically shown in Figs. 3 and 4, wherein IV indicates the running surface of roller 4, V the running surface of roller 5 and VI that of roller 6. Under a certain angle of inclination ϕ of the plane of rotation S—S in respect to the racing surface P (in Fig. 3 at an angle $\phi=90^\circ$) the running surface IV, V, VI of all rollers 4, 5, 6 contact the course surface P. With increasing angle ϕ the differently shaped running surfaces IV and VI of the auxiliary rollers 4 and 6 will one by one disengage from the racing surface P until only the surface V of main roller 5 remains in contact with the racing surface P. In the shown embodiment the main roller 5 has the largest diameter and its running surface V has a spherical shape.

As shown in Fig. 5 the main roller 5 which preferably is made from a light metal is mounted in the frame 1 by means of a bolt 8 and two ball bearings 9. The surface of said roller 5 is coated with a lining 1 of a suitable elastic and sufficiently hard and rough material, such as rubber. The rear auxiliary roller 6 is also spherically shaped but has a smaller diameter than the roller 5. The front auxiliary roller 4 has the shape of a narrow wheel with an elastic tire. At the front end of the adequately stiffened frame 1 a suitable jump off abutment 17 is provided in the shape of a screwed-in plug made of rubber or similar material.

Fig. 6 shows a somewhat modified arrangement of the rollers in the skate frame. The skate frame 15 is provided with a central web 14, which supports a ball bearing 12 firmly held therein by suitable attachment rings. Said ball bearing supports the complementary halves 10, 11 of the roller which parts are connected by a bolt 13. The web 14 extends rearwards in a braking spur 16 as shown in Fig. 7.

When racing in a straight direction the plane of rotation S—S of the rollers 4, 5, 6 is approximately perpendicular to the racing surface as indicated in Fig. 3 and all three rollers 4, 5, 6 contact with their running surfaces IV, V, VI the racing course P tending to guide the skate in a straight direction. The skate resting with all three rollers upon the race course has a considerable stability, as there is no possibility of easy tipping forwards or rearwards. If, however, the skate is inclined laterally, into the position shown in Fig. 4, only the main roller (running surface V) remains finally engaged with the course surface P whilst both auxiliary rollers 4 and 6 with their profiles IV and VI are successively disengaged therefrom. The entire load is then resting

on the main roller 5 of spherical shape which offers to any change of the racing direction a far smaller resistance than a set of two or more rollers arranged behind each other and uniformly loaded. Therefore the disclosed arrangement according to the invention allows racing in curves of even small radius simply by a rolling movement of the main roller eliminating any skidding and undesirable friction of the auxiliary rollers. An almost ideal rolling motion in curves results from the rolling body 5 running on the course P with only a narrow contacting strip of the width p.

It is to be understood that it is not indispensable that in curve racing only the main roller 5 contacts the race course P. It may be admissible and even desirable in view of improving the stability that some of the auxiliary rollers 4 or 6 transiently contact the course surface. However, it is essential that a prevailing part of the load rests on the main roller 5. This requirement is fulfilled if the main roller 5 is arranged between the auxiliary rollers 4 and 6.

The spherical shape of the running surface V of the main roller is particularly suitable, because it guarantees a permanently uniform engagement with the racing course surface P at any angle of inclination ϕ and a maximum stability in transverse direction. The basic idea of the present invention may, however, be carried into effect with other suitable shapes of the main roller 5, if only the selected shape matches the profiles of the auxiliary rollers 4 and 6 in such manner that the said auxiliary bodies 4, 6 are at certain inclinations of the plane S-S of rotation lifted out of engagement with the course surface P. Preferably the main roller 5 has the largest diameter d in order to reduce to a minimum the losses during the race upon this utmost loaded body.

The jump-off abutment 17 through its engagement with the course surface P facilitates the jumping off and thereby also sudden turns and high racing speeds. By means of the braking spur 16 (Fig. 7) efficient braking may be performed through its engagement into the racing course which is of special importance when playing hockey. The constructional embodiment shown in Fig. 6 involving a two-part rolling body 10, 11 and a central web 14 facilitates a very simple arrangement of the braking spur 16, which may also be provided with a projection like the jump-off abutment 17. It is to be understood that instead of two auxiliary rollers a greater number of such rollers may be provided thus attaining the advantage of better overcoming any unevennesses of the course.

In Fig. 8 which shows still another embodiment of the present invention, 24 is the frame of a roller skate wherein by means of a pivot 23 and ball bearings 22 a metallic roller 21 is rotatably supported, said roller 21 being provided with a rubber lining 25. At both sides of said roller 21 border discs 26 of a hard steel plate with a sharp outer edge 27 are attached thereto by rivets 28, said edge 27 being approximately at the same level as the surface of the rubber lining 25.

In normal straight racing, the skate runs on the course with its elastic lining 25 and the edges 27 are ineffective. Only when the central plane of the skate inclines towards the course to a sufficient extent the sharp edge 27 comes into engagement with the course surface. In view

of the fact that the material wherof the disc 26 is made is very hard, a very efficient engagement is thus attained without any risk of damaging the edge 27. The roller according to the present invention which may also be of any other suitable profile than that illustrated thus combines in itself the necessary features ensuring an elastical racing, as well as the possibility of an effective engagement for jumping off and braking, and an outstanding durability.

In the embodiment shown in Fig. 9 the roller 31 is laterally provided with hard discs 29 having a circumferential teething 30 to enable a still sharper engagement.

It is also possible to provide instead of sharp edges blunt rims or even rounded off rims with a roughened surface. The nature and hardness of the course is decisive for the choice of the respective design. Likewise the connection between the rims and the remaining portions of the roller may be performed in any suitable manner and the border discs may be exchangeable. It is to be noted, however, that the material of the rims is to be harder than the material of the running surface of the rollers.

Some of the rollers, preferably the foremost, may also be provided with a one-way free motion preventing any backward rotation so that the respective roller may be used as a jump off.

The roller skates according to this invention are, as far as speediness, possibility of racing in sharp curves, safety of control and fitness for figure-skating, and hockey competitions is concerned, fully equivalent to edge-skates which are suitable only for ice courses.

While specific embodiments of my invention have been shown and described in detail to illustrate the application of the principles of my invention, it will be understood that the same may be otherwise embodied without departing from such principles.

What I claim as my invention is:

1. In a roller skate the improvement comprising in combination a supporting frame, at least two auxiliary rollers and an intermediate main roller in tandem formation, fixed axles for said rollers mounted in said frame, each of said rollers having a transverse convex running surface contacting the supporting surface while the rollers rotate in a plane essentially perpendicular to the supporting surface, the convex running surface of the main roller having a greater radius of curvature than the running surfaces of the auxiliary rollers.

2. In a roller skate the improvement comprising in combination a supporting frame, at least two auxiliary rollers and an intermediate main roller in tandem formation, fixed axles for said rollers mounted in said frame, each of said rollers having a transverse convex running surface contacting the supporting surface while the rollers rotate in a plane essentially perpendicular to the supporting surface, the convex running surfaces of the rollers having different radii of curvature, the running surface of the main roller being curved least.

3. In a roller skate the improvement comprising in combination a supporting frame, at least two auxiliary rollers and an intermediate main roller in tandem formation, fixed axles for said rollers mounted in said frame, each of said rollers having a transverse convex running surface and at least the main roller a spherically shaped running surface, the running surfaces of all

three rollers contacting the supporting surface while the rollers rotate in a plane essentially perpendicular to the supporting surface, the spherically shaped running surface of the main roller having a greater radius of curvature than the running surfaces of the auxiliary rollers.

EUGEN KARDHORDO.
